UNITED STATES PATENT OFFICE.

SAMUEL M. TEETER, OF ST. LOUIS, MISSOURI.

CAN-OPENER GUIDE.

Application filed January 28, 1924. Serial No. 689,177.

To all whom it may concern:

Be it known that I, SAMUEL M. TEETER, a citizen of the United States, residing at Saint Louis, in the county of Saint Louis 5 and State of Missouri, have invented certain new and useful Improvements in a Can-Opener Guide, of which the following is a specification.

This invention appertains to devices for 10 opening cans and the primary object of the invention is to provide a novel can opener which is so constructed that the same will cut the top of the can entirely off of the same and permit the can to be used over 15 again with the addition of a lid for home canning purposes.

A further object of the invention is the provision of an improved can opener having a novel cutting blade, which is so shaped, 20 as to turn down a flange on the remaining portion of the top of the can during the opening of the can, whereby the said flange will act as a retainer for the new can top, when the same is associated with the can.

25 A further object of the invention is the provision of a novel guide and holder for the can opener, whereby the can opener will be held in correct position relative to the can during the opening operation, so 30 that a complete disk of circular shape will be cut from the can top.

A still further object of the invention is 35 to provide an improved can opener of the above character, which will be durable and efficient in use, one that will be simple and easy to manufacture and one which can be placed upon the market at a reasonable cost.

With these and other objects in view, the 40 invention consists in the novel construction, arrangement and formation of parts, as will be hereinafter more specifically described, claimed and illustrated in the accompanying drawings, in which drawings:

Figure 1 is a side elevation of the improved can opener showing the same in use, 45 the can being partly broken away, the novel guide for the can opener being shown in diametric section.

Figure 2 is a top plan view of the can 50 opener and the guide, and

Figure 3 is a bottom plan view of the guide for the can opener.

Referring to the drawings in detail, 55 wherein similar reference characters designate corresponding parts throughout the several views, the letter A generally indi-

cates the can opener; B the novel guide therefor and C a can on which the opener and guide can be used.

The opener A comprises a flat shank 5 having one end anchored in a suitable manipulating hand grip 6. The outer end of the shank 5 has riveted or otherwise secured to its lower surface as at 7 a metal strip 8. The forward end of the metal strip 8 is provided with a depending pivot 9 and a forwardly extending punching point 10. As shown the punching point 10 is located at right angles to the depending pivot 9 and in parallel relation to the shank 5. The opposite end of the strip 8 is provided with a depending cutting blade 11 which forms a vital part of the present invention. The opposite side edges of the cutting blade 11 are beveled from the outer face toward the inner face to provide opposite cutting edges and the lower end of the blade is beveled downwardly from the outer face of the blade toward the inner face of the blade to provide a cutting and punching point 12. The cutting edges of the blade and the punching and cutting point 12 are so formed as to make a clean cut of the circular disk cut from the can top as will be hereinafter more fully described and to form a depending flange on the portion of the top after the disk has been cut therefrom.

The improved guide B also forms a vital part of the invention and comprises a circular top 15 and a depending flange 16 which is adapted to snugly receive the upper end of a can and to engage the side walls thereof. The axial center of the top wall 15 is provided with a pivot opening 17 for the reception of the pivot 9, for a purpose, which will also be hereinafter more fully described. The top 15 at a point adjacent to the flange 16 is provided with a slot or opening 18 through which the cutting blade 11 is adapted to project for permitting the blade to cut the can top.

This guide B is so formed, that it will be necessary for the shank 5 to be always held in a horizontal position thereby insuring of the correct and easy cutting of the can top.

The can C is of course the usual type employed for canned vegetables and the like and includes the side wall 20 and the top wall 21.

In use of the improved can opener the 110 guide 15 is placed upon the top of the can as shown in Figure 1 of the drawing, after

which the can opener is held in a vertical position and the penetrating point 10 is inserted through the opening 17 and forced through the can. Now this insures the 5 punching of the can at the center thereof. After the point 10 has been driven through the can top 21 the can opener is moved down to a horizontal position and the cutting blade 11 is forced through the slot 18 into 10 the can. The can is now tightly held in one hand and the can opener in the other and the can opener is given a rotary movement around the can, which will effectively sever a disk from the top thereof. As the disk is 15 being severed a flange 22 will be formed on the remaining portion of the top, which will serve as means for holding a snap lid in position on the can. It is desirable to cut the top from the can in such a manner that the 20 can can be used over again for home canning purposes and when the top is severed in the manner described, ordinary snaps for the top such as are employed on syrup cans can be bought and associated with the can. 25 If desired the top can be sealed by the use of suitable wax or the like.

Changes in details may be made without departing from the spirit or the scope of this invention.

What I claim as new is:

1. A can opener comprising a shank, a handle at one end of the shank, a penetrating point and pivot at one end of the shank, and a cutting and penetrating blade carried by the shank and disposed at a point intermediate its ends, and a guide for engaging the top of the can for detachably receiving the penetrating point and pivot and the cutting blade.

2. A can opener comprising a shank, a penetrating point and pivot at the forward end of the shank, a cutting blade carried by the shank at a point intermediate its ends, a guide including a circular top and a depending flange for receiving the top of the can, the top wall having an axial opening therein for detachably receiving the penetrating point and pivot, and a slot adjacent to the flange for detachably receiving the cutting blade.

In testimony whereof I affix my signature.
SAMUEL M. TEEETER.
